Inventor.

United States Patent Office.

ALBERT L. MUNSON, OF NEW HAVEN, CONNECTICUT.

Design No. 4,017, dated May 10, 1870.

DESIGN FOR A HAND-STAMP.

The Schedule referred to in these Letters Patent and making part of the same.

I, ALBERT L. MUNSON, of New Haven, in the county of New Haven and State of Connecticut, have invented and produced a new and original Design for Hand-Stamps, of which the following is a specification.

The nature of my design is fully and clearly represented in the accompanying drawings, to which reference is made, and which said drawings form part of this specification, and represent in—

My invention relates to an improvement in handstamps, especially designed for marking clothing and kindred articles.

Claim.

I claim as my invention—

The design of the shape and configuration of a hand-stamp, as shown, all substantially as herein described and illustrated in and by the accompanying drawings.

ALBERT L. MUNSON.
